UNITED STATES PATENT OFFICE.

SETH M. GOODER, OF CHICAGO, ILLINOIS.

UNDERPINNING AND METHOD OF MAKING THE SAME.

Application filed October 26, 1927. Serial No. 228,717.

When an excavation is made beside a building, to a depth greater than the depth of the foundation of the building, such foundation must be underpinned to prevent collapse. The usual method is to build underneath the wall to be supported a new foundation that does not rise to the bottom of the old foundation. Jacks are then placed on top of the new foundation and the wall supported therefrom. Then, when excavation goes on beside the building and piles driven or other work done that may cause the new foundation to settle, the jacks are operated to maintain the underpinned building at its initial level. After the settling has been completed the space between the top of the new foundation and the bottom of the old is filled in, the jacks being removed as the filling progresses.

Sometimes there is considerable disturbance of the bed on which the new foundation rests, before the jacks may be removed. Thus, for example, if piles are driven down close to this new foundation, the top of the foundation will tend to swing outwardly, due to the earth pressure on the inside and the failure of the support underneath the same on the outer side. On account of the considerable space usually left between the top of the new foundation and the bottom of the old, this space being bridged only by the removable jacks, the support for the original wall is very insecure and such wall may swing out at the bottom while the new foundation moves out at the top.

The object of the present invention is to produce a simple and novel method of underpinning a wall so that the new foundation may be brought much closer to the bottom of the old foundation, before the jacks are applied, than has heretofore been possible, thereby securing much greater stability and lessening the danger of lateral deflection while excavations are being made or other work done beside the new foundation.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is an elevation of a fragment of a wall supported by jacks from a new foundation in accordance with the present invention; Fig. 2 is a view similar to Fig. 1 showing the condition of the foundation after removal of the jacks; Fig. 3 is a vertical section taken through the wall and underpinning at right angles to the plane of Fig. 1; Fig. 4 is a plan view of one of the supporting plates for the jacks; and Fig. 5 is a side elevation of one of the jacks, its supporting plate being shown in cross-section.

Referring to the drawing, 1 represents the wall to be underpinned. As shown in Figs. 2 and 3, 2 is a new foundation built underneath the wall. Because of the necessity of having adjusting means between the foundation and the old wall, the foundation cannot be brought up into contact with the bottom of the old wall in the first instance. As heretofore stated, it has been customary to leave enough space between the foundation and the wall above it to receive ordinary screw jacks. I have devised a way of greatly shortening this distance so as to bring the two wall structures more nearly into contact with each other. In accordance with my invention I form in the top of the new foundation a series of pockets opening downwardly and open on one or both sides of the foundation. These pockets are conveniently in the form of slots extending completely through the foundation. When the foundation has set sufficiently to permit the weight of the building to be imposed on the same, I place jacks in the slots or notches or pockets, suspending these jacks from the upper ends of their bodies or bases, instead of supporting them from their lower ends. Therefore, since only a small part of the base or stationary portion of the jack need lie above the top of the new foundation, the foundation may be brought to within a distance from the bottom of the building wall not much greater than the height of the top of the movable portion of the jack above the top of the stationary portion when the screw is down.

The jacks may take various forms. Thus, as shown in Figs. 4 and 5, it may consist of what may be termed a nut 5 having at the top a flange 6 and, underneath the flange, a radial lug 7; the usual jack screw 8, with

its head 9, being screwed through this nut. The nut may be said to constitute the base or stationary portion of the jack. For convenience, I provide an auxiliary base member which, in the arrangement shown, takes the form of a channel beam 10 containing a hole 11 to permit the passage of the body of the nut 5 but not the flange, and a notch 12 adapted to receive the projection 7 and prevent the nut from turning.

When a jack is to be placed in position, the two parts thereof, namely the jack proper and the auxiliary base, are assembled, with the flange resting in the bottom 15 of the channel of the auxiliary base and the jack screw screwed down as far as it will go. This unit is then placed opposite one of the slots or notches and is moved laterally so that the channel passes over the top of the 20 foundation and the main portion of the screw and the lower portion of the nut of the jack enter the notch or slot.

Allowing for clearance, to permit the easy application and removal of the jacks, 25 only a few inches of space need be left between the top of the new foundation and the underside of the old, whereas prior practices have made it necessary to leave a space several feet high.

When the new foundation is subsequently 30 to be completed, the jacks are removed a few at a time and the notches in the new foundation and the intervening space between the latter and the bottom of the old 35 foundation are filled, preferably with concrete, as indicated at 13 in Fig. 2; the dotted line 14 representing the contour of the new foundation as initially built, and the line 15 indicating the top of the completed new 40 foundation and the bottom of the old wall or foundation.

The utility of my invention, aside from 45 overcoming the necessity of employing so-called drums as the body members of jacks, will be apparent from inspection of Fig. 3. It will be seen that if the usual type of jack were set on top of the new foundation, this 50 foundation would have to stop at about the level of the bottom of the groove, causing the original wall to be supported from the new foundation on comparatively long struts or posts. In accordance with my invention, however, the effective top of the new foundation is very near the underside of the old 55 wall, so as to permit the employment of very short supporting elements or posts.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. The method of underpinning a wall preparatory to making an excavation beside the same, which consists in building underneath and up to within a short distance below the wall a foundation having notches in the top, placing on the foundation members each having a stationary base element spanning one of the notches and a vertically movable power element extending through the base element and down into the corresponding notch, and adjusting said power elements to cause the weight of the wall to be imposed upon the same.

2. The method of underpinning a wall and temporarily supporting the same, which 80 consists in building underneath and up to within a short distance below the wall a foundation having notches in the top thereof, placing on the foundation members each having a stationary base element spanning one 85 of the notches and a vertically movable power element passing through the base element and extending down into the corresponding notch, and adjusting said power elements to cause the weight of the wall to be imposed upon the same and the wall to be held at the desired level when the foundation settles.

3. The method of underpinning a wall and temporarily supporting the same which 95 consists in building underneath and up to within a distance less than the height of a jack screw below the wall a foundation having notches in the top and opening out of the side thereof, inserting between the foundation and the wall jacks each comprising a base member resting on the foundation at opposite sides of one of the notches and a screw extending into the corresponding notch, and operating the jacks to cause the 100 weight of the wall to be imposed upon the screws.

4. The method of underpinning a wall and maintaining the latter at the desired level during settling of the underpinning, which 110 consists in building up to within a distance less than the height of a jack screw below the wall a foundation having notches in the top and opening out of the side thereof, inserting between the foundation and the wall jacks each comprising a base member resting on the wall at opposite sides of one of the notches and a jack screw extending into the corresponding notch, adjusting the 115 screws to cause the weight of the wall to be imposed thereon, and thereafter making such 120 adjustments of the screws, during settling of the foundation as may be necessary to maintain the wall at the desired level.

In testimony whereof, I sign this specification.

SETH M. GOODER.
